COMBINED CLOCK AND SANDGLASSES

Willard Rush Cullen, 214 Racine St., Delavan, Wis.

Filed Apr. 11, 1962, Ser. No. 69,668

Term of patent 3½ years

(Cl. D42—7)

FIGURE 1 is a front elevational view of a combined clock and sandglasses showing my new design;

FIGURE 2 is a top plan view thereof;

FIGURE 3 is a right-end elevational view thereof;

FIGURE 4 is a cross-sectional view thereof taken on line 4—4 of FIG. 1;

FIGURE 5 is a cross-sectional view thereof taken on line 5—5 of FIG. 1; and

FIGURE 6 is a rear elevational view thereof, on a reduced scale.

I claim:

The design for a combined clock and sandglasses, as shown.
